UNITED STATES PATENT OFFICE.

CHARLES ALGERNON PARSONS, OF NEWCASTLE-UPON-TYNE, ENGLAND.

SCREW-PROPELLER.

SPECIFICATION forming part of Letters Patent No. 700,365, dated May 20, 1902.

Application filed December 22, 1900. Serial No. 40,774. (No model.)

To all whom it may concern:

Be it known that I, CHARLES ALGERNON PARSONS, engineer, a subject of the King of Great Britain and Ireland, residing at Heaton 5 Works, Newcastle-upon-Tyne, in the county of Northumberland, England, have invented certain new and useful Improvements in and Relating to Screw-Propellers, (for which I have made application for Letters Patent in 10 Great Britain, No. 9,792, bearing date May 28, 1900;) and I do hereby declare that the following is a full, clear, and exact description of the same.

My invention relates to screw-propellers 15 for fast ships, especially to those for use where the shaft revolves with high angular velocity. I find by experiment that the cavitation which attends high-speed propellers arises principally in two places—namely, at the 20 back faces of the blades near the tips and around the conical tip of the propeller-boss behind the blades.

The object of my invention is to remove or 25 reduce such cavitation.

According to the experiments of Dines and others it has been established that the normal pressure on a plane moved at small inclinations through air or water varies approximately as the angle of inclination and 30 the square of the velocity of motion. Now in a screw-propeller of the usual pitch ratio—say from one to fifteen pitch coefficient—the angle of inclination of the blade to the direction of motion through the water is approximately the same for such distances from 35 the shaft-line as lie outside about two-fifths of the radius of the propeller-circle, while the velocity of these points through the water varies approximately as the distance from the shaft. From this it follows that the pressure upon the water of any element of the blades (between the above limits) will vary approximately as the square of the distance of the element from the shaft-line. In high- 40 speed vessels when the water-pressure are great cavitation first commences near the tips of the blades (as I have proved experimentally) and extends toward the roots of the blades as the speed or slip ratio of the propeller is increased.

The cavitation which is found to take place around the conical end of the boss abaft the propeller is due to the rotational velocity imparted to the water in the vicinity of the boss by the normal action of the blades and also 55 by their skin and eddy friction on the water, which rotational velocity increases rapidly as the water tends to close in around the after cone, following the principle in hydrodynamics that the angular momentum in a vortex 60 tends to remain constant. The angular velocity of the water around the cone is therefore much in excess of that of the propeller-cone itself.

My invention consists, first, in reducing 65 the cavitation which takes place at the back faces of the propeller-blades near the tips by forming the blades with a reduced pitch near their tips.

The second part of my invention consists 70 in providing small vanes on the propeller-cone adapted to prevent cavitation around the cone and to utilize for propulsion some of the rotational energy of the water close to the propeller-cone, which is lost with the type 75 of propellers in ordinary use.

To obtain a high mean slip ratio and thrust without producing serious cavitation has been the object of many inventors; but their efforts to effect this end have hitherto been 80 made, among other things, in the direction of increasing the pitch of the blades toward their points. I have ascertained that the desired effect is produced by forming fast-running propellers with a reducing pitch toward 85 their tips, the reduction commencing about one-half to two-thirds outward from the boss or blade root, such reduction of pitch increasing to about a ten-per-cent. reduction at the blade-tips. Theoretically also it would 90 appear, first, that this variation of pitch should be such that the slip ratio at any given distance from the shaft should be in inverse proportion to the square of that distance; second, that cavitation would commence simultaneously over a large area of propeller-blade thus constructed; third, that such propellers could be run faster without producing cavitation, while at the same time effecting 95 a greater mean slip ratio and thrust than 100

would be possible with propellers constructed with blades of constant or increasing pitch toward their points. I have confirmed this by experiments on propellers constructed according to my invention which is based on this theory.

In order to clearly explain the difference between an ordinary propeller and one constructed according to my invention, I have appended two sheets of drawings, in which—

Figures 1 and 2 are elevation and plan, respectively, of an ordinary propeller, the latter view showing blade-sections *a*, *b*, *c*, *d*, *e*, and *f* on the lines *A A*, *B B*, *C C*, *D D*, *E E*, and *F F*, respectively, of Fig. 1. A diagram of the pitch variation of this propeller is also shown in Fig. 2. Figs. 3 and 4 are elevation and plan, respectively, of my new construction of propeller with reduced pitch, the plan showing blade-sections *g*, *h*, *j*, *k*, *m*, and *n* on the lines *G G*, *H H*, *J J*, *K K*, *M M*, and *N N*, respectively, of Fig. 3. A diagram of the pitch variation of my propeller is also shown in Fig. 4 for comparison with that shown in Fig. 2. Figs. 5 and 6 are elevation and plan of a propeller provided with vanes. Fig. 7 is a section through *A A* of Fig. 5, drawn to an enlarged scale.

The first part of my invention is illustrated by Figs. 1 to 4, inclusive.

In the propellers illustrated in Figs. 1 and 2 the angle of inclination of the blade from section *c c* outward to the tip of the blade is approximately constant, while the pitch of the blade increases continuously from *c c* outward to the tip, but is constant from *c c* inward to the root-section *f f*. A diagram representing the pitch variation of the propeller seen in Fig. 2 may be obtained in this manner: Along the horizontal axis of the propeller from its intersection with the vertical blade-axis set off a distance *p* equal to one-fourth of the pitch of the blade at the root-section *f f* and erect here a perpendicular line. Set off along this perpendicular line a distance *P'* equal to the radius of the root-section *f f*. Now since the pitch of the blade does not vary at the three sections *e e*, *d d*, and *c c* distances *P*², *P*³, and *P*⁴, corresponding respectively to the radii of these sections, may be set off along this perpendicular line. The pitch of the blade increases, however, from section *c c* outward. Set off, therefore, distances *q* and *r* to represent one-fourth of the pitch of the section *b b* and *a a*, respectively. Erect perpendiculars *Q*⁵ and *R*⁶, their lengths corresponding, respectively, to the radii of sections *b b* and *a a*. Then a curve drawn through the points 1, 2, 3, 4, 5, and 6 will represent the pitch variations of the propeller-blade, while a line from each point drawn to the intersection of the horizontal and vertical axes of the propeller gives the major axis, and consequently the inclination of each blade-section. It will be

observed that sections *a a* and *b b* have the same inclination to the direction of motion as each other and that the inclination of section *c c* varies very little from them.

Referring now to the propeller constructed according to my invention and illustrated in Figs. 3 and 4, the pitch of the blade is constant from the root-section *n n* outward to a point about midway between the sections *k k* and *j j*; but it decreases from this point outward to the tip of the blade. The line of pitch variation for this propeller may be obtained in the same manner as in the case just described. Let the distance *w* from the vertical axis of the blade represent one-fourth of the pitch of the three sections *n n*, *m m*, and *k k* and distances *u*, *t*, and *s* represent one-fourth of the pitch at sections *j j*, *h h*, and *g g*, respectively. By erecting perpendicular lines from the horizontal axis at these distances and setting off lengths thereon corresponding to the radii of the various sections points 7, 8, 9, 10, 11, and 12 are obtained, and the line passing through them represents the pitch variation of my propeller. As is also the case in Fig. 2, a line drawn from these points to the intersection of the horizontal and vertical axes of the propeller gives the inclination of the various blade-sections to the direction of motion. I have found that propellers constructed as just described with reference to Figs. 3 and 4 can be run at a higher speed without the production of cavitation and with a higher mean slip ratio and thrust than has hitherto been possible.

In carrying the second part of my invention into effect as illustrated by Figs. 5, 6, and 7, I provide small vanes *v v* on the cone *x* of the propeller-shaft *y*, which vanes may be parallel to the shaft, as shown, or set at a moderate angle thereto, with a pitch of the same or opposite hand to the propeller itself. In my experiments I have found that when three vanes are provided on the cone and set parallel to the shaft, as illustrated, with their outer edges practically parallel to the center line of the shaft the cavitation produced around the cone *x* at a given speed is largely reduced or entirely prevented. As hereinbefore explained, the angular velocity of the water around the cone is much in excess of that of the propeller-cone itself; but vanes such as those just described retard the water vortex around the cone with two beneficial results—first, some of the angular momentum of the water vortex that would otherwise be lost is imparted to the vanes, and consequently assists in rotating the shaft, and, secondly, owing to the diminution of the angular velocity of the water around the shaft the water more easily closes in and presses on the cone abaft the propeller-boss, thus imparting an additional forward thrust to the shaft.

What I claim as my invention, and desire to secure by Letters Patent, is—

1. A screw-propeller provided with blades constructed with a reduced pitch toward their tips, the reduction commencing from about one-half to two-thirds outward from the blade-roots, substantially as described.

2. A screw-propeller having vanes secured

to the propeller-cone behind the blades, substantially as described.

In witness whereof I have hereunto set my hand in presence of two witnesses.

CHARLES ALGERNON PARSONS.
